UNITED STATES PATENT OFFICE.

RICHARD F. MURRAY, OF FORT EDWARD, NEW YORK.

PAPER-MAKING MACHINE.

1,240,589.

Specification of Letters Patent. Patented Sept. 18, 1917.

Application filed June 9, 1917. Serial No. 173,776.

To all whom it may concern:

Be it known that I, RICHARD F. MURRAY, a citizen of the United States, residing at Fort Edward, in the county of Washington and State of New York, have invented certain new and useful Improvements in Paper-Making Machines, of which the following is a specification, reference being had to the accompanying drawings.

10 This invention relates to paper making machines, and has for its primary object to provide certain improvements in the headbox mechanism from which the paper pulp is fed, whereby the machine may be operated 15 at very high speed to produce a high-grade product and with a minimum of wear upon the several mechanical parts.

It is one of the particular objects of the present invention to provide an improved 20 adjustable apron board whereby wear upon the wire agitator which receives the pulp may be entirely obviated.

It is also another object of my invention to provide an improved sectional slice and 25 means for relatively adjusting the sections thereof, and additional means for vertically adjusting the slice as a unit to regulate the thickness of the paper pulp which is delivered to the apron board and to render the 30 same uniform.

It is also one of the important objects of the invention to provide deckle angles at opposite ends of the apron board hingedly connected to the adjustable slice and adapted 35 to extend outwardly over the wire breast roller and movable against one side of the slice so that the wire can be easily removed or placed upon the conveyer rollers.

And it is a further general object of the 40 invention to generally improve and simplify the construction of machines of the above character, whereby a considerable saving in time and labor is realized, as well as an appreciable economy in the use of the paper 45 pulp, the several parts of my improved headbox mechanism being of relatively simple construction and capable of application to the ordinary paper making machine now in general use.

50 With the above and other objects in view, my invention consists in the novel features of construction, combination, and arrangement of parts to be hereinafter more fully described, claimed, and illustrated in the accompanying drawings, in which,

Figure 1 is a fragmentary sectional view through the headbox of a paper making machine, showing the preferred embodiment of my invention applied thereto;

Fig. 2 is a top plan view;

Fig. 3 is a sectional view taken on the line 3—3 of Fig. 1; and

Fig. 4 is an elevation of the sectional adjustable slice.

Referring in detail to the drawing, 5 generally designates the headbox or vat which contains the paper pulp, and within this box a wire mesh roller 6 is arranged, the trunnions 7 of said roller being vertically movable in the end walls of the box. This 70 roller operates to continually agitate or stir up the paper pulp contained in the box or vat and to cross the fibers of the pulp.

8 designates the breast roll of an endless wire screen 9, said roll being suitably mounted at one side of the head box 5 and having one end of its axis operatively connected to one of the trunnions of the roller 6 by means of the endless belt indicated at 10.

Upon the wall of the headbox next adjacent to the conveyer roller 8, an angle bar 11 is arranged, the horizontal flange of said bar projecting over the upper edge of the box wall while the vertical flange of the bar extends downwardly upon the outer face of the wall. The latter flange of the angle bar is provided adjacent to its lower edge and in spaced relation to the opposite ends of said bar, with a threaded boss or lug 12. In bearing brackets 13 secured to the wall of the headbox 5, the vertically disposed shafts 14 are rotatably mounted, said shafts being threaded and operatively engaged in the respective lugs 12. The lower end of each shaft 14 has a bevel gear 15 fixed thereto, said gears being engaged by the similar gears 17 secured upon a shaft 16 which is supported in the arms or extensions 18 formed upon bearing brackets 13. This shaft is provided upon one end with a suitable hand wheel 19, whereby it may be conveniently rotated. A disk 20 is also secured upon said shaft and disposed between the arm 18 of one bracket and an angular lug 21 which is fixed to the bracket. A clamping screw 22 is threaded in this lug and is adapted to be adjusted into frictional binding engagement against the disk 20, whereby the shaft 16 will be held against rotation.

23 designates the apron board which ex-

tends over the horizontal flange of the angle bar 11, said board being provided with an angular portion 24 extending downwardly along the inner face of the wall of the headbox 5. The other longitudinal edge of the head board 23 is disposed substantially in vertical alinement with the axial center of the breast roll 8, but out of contact with the wire 9. At spaced points, bracket plates 10 25 are hingedly mounted upon the vertical flange of the angle bar 11, as shown at 26, to support the laterally extending portion of the apron board 23. As thus described, it will be seen that the apron board can be 15 readily adjusted vertically by simply rotating the shaft 16, whereby the vertical shafts 14 are turned in the threaded lugs 12. The edge of the apron board may thus be properly spaced from the wire 9. As shown in 20 Fig. 2, the upper surface of the apron board 23 may be provided with obliquely disposed, intersecting grooves. Either a plane or grooved apron board may be employed in accordance with the particular grade of 25 paper.

In conjunction with my improved apron board, I provide a sectional slice, whereby the thickness of the paper pulp fed over the board to the wire agitator 9 may be regulated as desired. This slice consists of a 30 series of plates or sections 27, each of which is provided on its upper edge with a laterally projecting, longitudinally extending flange 28. A bar 29 is provided in its ends 35 with angular arms 30 in which vertically disposed adjusting screws 31 have threaded engagement, the lower ends of said screws being rotatably mounted in the upper ends of standards 32 supported upon the walls of 40 the headbox. These standards are connected at their lower ends by the bar 33 resting upon the headbox wall. A pair of adjusting screws 34 is threaded in the flange 28 on each section 27 of the slice, the lower 45 ends of said screws being rotatably mounted in the bar 29. A lock nut 35 is threaded upon each screw 34 to engage the flange 28 and hold the slice section in its adjusted position. A similar lock nut 36 is also threaded 50 upon each of the adjusting screws 31 for engagement with the lugs 30. By adjusting the two screws 31 at opposite sides of the headbox, it will be understood that the several sections 27 of the slice may be raised 55 or lowered as a unit to space their lower edges from the bar 33. These several sections of the slice can also be individually adjusted by means of the screws 34.

The lower end of one of the standards 32 60 is provided with an outwardly projecting arm 36, in which one end of an adjusting screw 37 is swiveled for rotative movement. This screw has threaded engagement in an angular bracket 38 secured to one wall of 65 the headbox. By the rotation of this screw,

the sectional slice may be shifted longitudinally and disposed in the proper position.

Upon the standard 32 at each end of the adjustable slice, a deckle angle 39 is hingedly mounted, as at 40, and is adapted to extend laterally from the slice in parallel relation to the line of movement of the pulp over the apron board 23 adjacent to the opposite ends thereof as seen in Fig. 2, so as to prevent the lateral deflection of the pulp and consequent waste thereof. These deckle angles, by reason of their pivotal mounting, may be swung inwardly against the adjustable slice to a position at right angles to the line of movement of the pulp. The wire screen 9 can then be easily and quickly removed from the roller 8 or placed thereon. Of course, the usual deckle strap, indicated at 41, operates above the wire screen 9 to carry the paper pulp from the apron board 85 upon the agitator and retain the same on the latter.

From the foregoing description, the construction, manner of operation, and several advantages of my invention will be readily understood. Heretofore, it has been usual to arrange the slice on the opposite side of the breast roll 8 so that it held back a pond of water and the pulp stock. By mounting the fiber crossing roller 6 back of the adjustable slice, the strength and texture of the paper is greatly improved. The improved adjustable apron board prevents frictional wear upon the wire agitator which is caused by the canvas apron usually employed, dragging upon the wire. The use of such a canvas apron also makes it impossible to operate the machine at a high speed. With the improved apron, the machine can be operated at a maximum speed with entire 105 safety. This apron board may be readily adjusted vertically to space the same from the conveyer as desired. The sectional slice and means for adjusting the several sections enables the operator to improve the 110 product by preventing light and heavy streaks in the paper so that it will be of uniform consistency throughout. It will thus be appreciated that I have greatly increased the efficiency of paper making machinery by means of the present improvements and likewise reduced the manual labor incident to their proper operation. The several coöperating parts of the mechanism above referred to are, of course, susceptible 115 of some modification in their form, proportion and arrangement, and it is, therefore, to be understood that while I have herein disclosed the present preferred embodiment of the invention, I nevertheless 120 reserve the privilege of resorting to all such alternative constructions as may be fairly considered within the spirit and scope of the appended claims.

Having thus fully described my invention, 130

what I desire to claim and secure by Letters Patent is:

1. In a paper making machine, the combination with a head box, a breast roll and wire engaged thereon, of an apron mounted upon the head box and extending over the breast roll to direct the flow of the pulp to the wire, a vertically adjustable slice mounted upon the head box between the apron and the pulp pond, means for adjusting said slice, and means for vertically adjusting the apron independently of the slice. 65
2. In a paper making machine, the combination with a head box, a breast roll and wire engaged thereon, of a rigid apron board mounted upon the head box and at all times disposed in a horizontal plane to direct the flow of the pulp to the wire, a vertically movable slice, means for adjusting said slice with respect to the apron board, and means for independently adjusting the apron board vertically with respect to the wire. 70
3. In a paper making machine, the combination with a headbox, a breast roll and wire engaged thereon, an apron mounted upon the headbox and extending laterally therefrom above the breast roll, and deckle boards movably supported above the apron board and adjustable to a position in parallel relation to the pulp flow to extend over the wire or to an inoperative position at right angles to such flow. 75
4. In a paper making machine, the combination with a headbox, of a breast roll and wire engaged thereon, a rigid apron board mounted upon the headbox and extending laterally therefrom above the breast roll, and deckle boards pivotally mounted at one of their ends for swinging movement over the apron board adapted to be disposed in parallel relation to the pulp flow to extend over the wire, or movable to an inoperative position at right angles to the direction of the pulp flow. 80
5. In a paper making machine, the combination with a breast roll and wire engaged thereon, of an apron mounted between the breast roll and the pulp pond and extending over the wire, and deckle boards pivotally mounted at one of their ends for swinging movement over the apron to a position in parallel relation to the direction of flow of the pulp or at an angle with respect thereto. 85
6. In a paper making machine, the combination with a headbox, a breast roll and wire engaged thereon, of a rigid apron board mounted upon the headbox and extending over the breast roll to direct the flow of the pulp to the wire, an adjustable slice mounted upon the headbox between the apron board and the pulp pond, and a fiber crossing roller mounted within the headbox to direct the pulp toward the slice. 90
7. In a paper making machine, the combination with a headbox, a breast roll and wire engaged thereon, of an apron mounted upon the headbox to direct the pulp to the wire, a sectional slice mounted upon the headbox between the apron and the pulp pond, a fiber crossing roller mounted within the headbox to direct the pulp toward the slice, and means for independently vertically adjusting the sections of the slice. 95
8. In a paper making machine, the combination with a headbox, a breast roll and wire engaged thereon, of an apron mounted upon the headbox to direct the pulp to the wire, a sectional slice mounted upon the headbox between the apron and the pulp pond, a fiber crossing roller mounted within the headbox to direct the pulp toward the slice, means for independently vertically adjusting the sections of the slice, and additional means for vertically adjusting the slice sections as a unit. 100
9. In a paper making machine, the combination with a headbox, a breast roll and wire engaged thereon, of a vertically adjustable slice mounted upon the headbox, a fiber crossing roller mounted within the headbox to direct the pulp toward the slice, means for vertically adjusting said slice, and deckle boards pivotally mounted upon the slice for swinging movement to a position in parallel relation to the pulp flow, or to an inoperative position at right angles to such flow. 105
10. In a paper making machine, the combination with a headbox, a breast roll and wire engaged thereon, of a slice frame vertically movable upon the headbox, a slice vertically movable in said frame, a fiber crossing roller mounted within the headbox to direct the pulp toward the slice, means for vertically adjusting the slice upon the frame, means for vertically adjusting said frame, and deckle boards hingedly mounted upon the ends of the frame for swinging movement, whereby the same may be disposed in parallel relation to the line of pulp flow, or to an inoperative position at right angles to such flow. 110

In testimony whereof I hereunto affix my signature in the presence of two witnesses. 115
